No. 792,959.

PATENTED JUNE 20, 1905.

C. C. BAKEWELL.
CLAMP FOR TROLLEY WIRES.
APPLICATION FILED MAR. 31, 1905.

UNITED STATES PATENT OFFICE.

CRIS C. BAKEWELL, OF KAYLOR, PENNSYLVANIA, ASSIGNOR OF ONE-HALF TO T. W. MINFORD, OF KAYLOR, PENNSYLVANIA.

CLAMP FOR TROLLEY-WIRES.

SPECIFICATION forming part of Letters Patent No. 792,959, dated June 20, 1905.

Application filed March 31, 1905. Serial No. 253,194.

To all whom it may concern:

Be it known that I, CRIS C. BAKEWELL, a citizen of the United States, residing at Kaylor, in the county of Armstrong and State of Pennsylvania, have invented certain new and useful Improvements in Clamps for Trolley-Wires; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in clamping means for supporting electric wiring, &c., and comprises means whereby a trolley-wire may be readily adjusted in place and providing means for the purpose of making the parts interchangeable in the event of breakage or for other purposes; and the invention consists specifically in various details of construction and in combinations and arrangements of parts, which will be hereinafter fully described and then specifically defined in the appended claims.

My invention is illustrated in the accompanying drawings, in which—

Figure 1 is a side elevation of one of the sections of the clamp. Fig. 2 is a view of one end of the form shown in Fig. 1. Fig. 3 is a view of the opposite end to that illustrated in Fig. 2. Fig. 4 is a side elevation of a telescoping part of the clamp. Fig. 5 is a view in end elevation of the telescoping part shown in Fig. 4. Fig. 6 is a view of the opposite end of the showing in Fig. 4. Fig. 7 is a side elevation of the parts assembled together. Fig. 8 is a view in end elevation of the clamp as illustrated in Fig. 7. Fig. 9 is an elevation of the opposite end of the clamping device from that shown in Fig. 8, and Fig. 10 is a detail view showing a movable threaded wear-block.

Reference now being had to the details of the drawings by letter, A designates a shell having a chambered portion, the outline of which is cylindrical, and one wall of said chambered portion is projected, forming a clamping-jaw B, which has a recess B' in the inner face thereof, as shown clearly in the drawings. An

opening C (shown clearly in Figs. 1 and 2 of 50 the drawings) is formed into the chambered portion of said shell, said opening terminating at D, beyond which the chambered portion of the shell is continued. An aperture is formed transversely through the upper part 55 of said shell and adapted to receive a screw E, (shown clearly in the drawings,) and a recess F is formed in the upwardly-projecting portion of the shell and has the marginal wall thereof threaded to receive a screw for the 60 purpose of supporting the clamping mechanism.

K designates a hollow cylindrical member having a wing K', which is recessed, as at K'', upon one face thereof. The diameter of said member K is of such dimensions as to allow said member to telescope readily within the chambered portion of the shell A, as shown clearly in Figs. 8 and 9 of the drawings, and said wing K' when thus adjusted passes 70 through the opening C in the shell and has a limited rocking play within the latter. When the two clamping members are adjusted together in the manner shown in Figs. 8 and 9, it will be observed that the recesses B' and K'' 75 are opposed one to the other and adapted to form clamping means for holding a trolley or other wire. In order to hold the jaws in adjusted positions, I provide a rivet N, which passes through diametrically opposite and registering apertures in the shell and said telescoping member, the apertures in said member, it will be observed, being somewhat elongated in order to allow for a slight adjustment of 80 said member. Said rivet N is adapted to support the shell and keep it from spreading in case of extra or continued strain.

It will be observed that the upper portion of the member K is cut away, and a plate T is seated in said cut-away portion, being removably held therein, and said plate has threads engaged by the threads of the bolt E, whereby as said screw is tightened the cylindrical member K may be turned so that the integral jaw thereof will be held in clamping relation with 95 the jaw upon the shell A. By the provision of the plate T it will be observed that the same may be easily removed and a new one substi-

tuted therefor when the threads become worn, thereby effecting a saving in replacing the entire cylindrical shell K.

From the foregoing it will be observed that by the provision of a clamping mechanism as shown and described a simple and efficient means is provided for holding a trolley-wire and affording mechanism whereby in the event of one of the parts of the clamping device becoming defective the same may be easily and quickly replaced.

While I have shown a particular form of apparatus illustrating my invention, it will be understood that I may vary the same, if desired, as to details without in any way departing from the spirit of the invention.

Having thus fully described my invention, what I claim as new, and desire to secure by Letters Patent, is—

- 20 1. A clamping device for trolley-wires, comprising a shell having a cylindrical outlined chambered portion, one wall of which is projected to form an integral jaw, a cylindrical member adapted to telescope within said chambered portion and having an integral jaw adapted to have a rocking movement within an opening leading into said chambered portion of the shell, and means for holding the jaws in adjusted positions, as set forth.
- 25 2. A clamping device for trolley-wires, comprising a shell having a cylindrical outlined

chambered portion, one wall of which is projected to form an integral jaw, a cylindrical member adapted to telescope within said chambered portion and having an integral jaw 35 adapted to have a rocking movement within an opening leading into said chambered portion of the shell, a plate seated in a recessed portion of said member and having threads in a grooved portion of said plate, means for 40 holding the jaws in adjusted positions, and a bolt passing through registering apertures in said shell and engaging the threads of said member, as set forth.

3. A clamping device for trolley-wires, comprising a shell having a shouldered portion and an integral jaw projecting from one side of said shell, a cylindrical member telescoping within said shell and provided with an integral jaw, a plate seated in a recessed portion of said cylindrical member and provided with a recess with a threaded wall, a screw passing through the threaded aperture in said shell and engaging the threads of said plate, whereby the cylindrical member may be 50 turned as the screw is operated, as set forth.

In testimony whereof I hereunto affix my signature in presence of two witnesses.

CRIS C. BAKEWELL.
